UNITED STATES PATENT OFFICE.

EDWARD M. HEWLETT, OF SCHENECTADY, NEW YORK, ASSIGNEE TO GENERAL ELECTRIC COMPANY, A CORPORATION OF NEW YORK.

SWITCH.

1,275,918.

Specification of Letters Patent. Patented Aug. 13, 1918.

Application filed May 9, 1914. Serial No. 837,596.

To all whom it may concern:

Be it known that I, EDWARD M. HEWLETT, a citizen of the United States, residing at Schenectady, in the county of Schenectady, State of New York, have invented certain new and useful Improvements in Switches, of which the following is a specification.

My invention relates to switches and insulating supports, and more especially to apparatus intended for very high voltages; and it comprises various novel features of construction and combinations and arrangements of parts. Among the advantages obtainable in connection with my invention are the ability to deal with voltages exceeding even the very highest at present in commercial use,—180,000 to 200,000 volts, for example,—and the avoidance of corona troubles. How these and various other advantages may be obtained in accordance with my invention will appear from the detailed description hereinafter of a particular high tension switch apparatus that is the best practical application at present known to me, while the scope of the invention will be indicated in my claims.

In the accompanying drawing, Figure 1 is a side view of a high tension disconnecting switch constructed in accordance with my invention;

Figs. 2 and 3 are similar fragmentary views on a larger scale illustrating details of construction of the insulating supporting structures, certain parts being in section;

Fig. 4 is a fragmentary detail view of the structure shown at the right of Fig. 3 turned about thirty degrees to the left from its position in that figure;

Fig. 5 is a plan view corresponding approximately to Fig. 3, certain lower parts being omitted;

Figs. 6 and 7 are fragmentary detail views of the switch mechanism as seen from the left and the right of Fig. 1, respectively, certain parts being shown in section or partially broken away.

Referring first to Fig. 1, it will be seen that the switch comprises a cylindrical blade 1—preferably hollow, as indicated in Figs. 6 and 7—pivoted at one end to a terminal or contact 2 to which the conductive cable 3 is

connected, and adapted at its other end to engage a terminal or contact 4 to which the conductive cable 5 is connected. The contacts 2 and 4 are mounted and secured on insulating supporting structures 6 and 7 each consisting of a plurality of post insulators arranged pyramid fashion. The structures 6 and 7 are shown in an upright position, 60 with the switch proper uppermost, as though their bases were secured to a floor or a platform,—and for clearness and convenience this arrangement will be assumed throughout the following description. In practice, 65 however the whole apparatus may be inverted and secured to the ceiling of a powerhouse or a sub-station, or turned on one side and secured to a wall, or mounted in any other convenient manner. 70

As the supporting structures 6 and 7 shown are exactly alike, a description of one of them will suffice. Referring to Figs. 1, 2, 3, 4 and 5, it will be seen that the left-hand structure 6 comprises a sheet metal plate 10 that can conveniently be bolted in place; three lower hollow, frusto-conical, externally ribbed or fluted insulator posts 11 with their large ends secured on said base; a superstructure 12 above the insulators 11 secured to them at its side next the base by means of caps 13; another similar hollow insulator post 14 with its large end secured to the other side of the superstructure 12; and means on the other end of said insulator post 14 for securing the element to be supported thereto,—this element being in the present case the contact 2. The insulator posts 11 and 14 may be of ceramic or other material,—as porcelain or bisque, for example,—and they may be made either in one piece or in a plurality of pieces secured together as shown in my Patent No. 1,077,711, granted November 4th, 1913, and of about the same external form as those therein shown. The lower ends of the insulators 11 are secured to the plate 10 (see Fig. 2) by means of clamps 15 externally engaging them, as shown in my patent aforesaid, and the caps 13, also, (see Figs. 3 and 4) are the angularly adjustable caps of my said patent. The superstructure or platform 12 is preferably a rigid circular casting having outstanding ear portions 16 (see Fig. 5) which

overlie the upper ends of the insulators 11 and to which the caps 13 are screwed, bolted or otherwise secured. The lower end of the insulator 14 is, again, secured to the super-
5 structure 12 by means of a clamp 17 externally engaging it (Figs. 3 and 5), as shown in my aforesaid patent, and the contact 2 is secured on the upper end of said insulator 14 by means of a cap 18 (see Fig. 6) such
10 as shown in said patent.

Referring to Figs. 1 and 6, it will be seen that the left-hand switch contact 2 is an upwardly opening U-shaped part, and that the contact or end piece 21 of the switch
15 blade 1 fits between the sides of the U and is pivotally secured by a bolt or pin 22. It will also be seen that from the bottom portion of the U projects a sleeve 23 in which the conductor of the cable 3 is soldered or
20 otherwise secured and connected. The edges of the contact part 2 are swelled into round beads to avoid corona, and all the other parts are rounded as much as possible for the same purpose.

25 Referring, now, to Fig. 7, it will be seen that the right-hand switch contact 4 is in general form and arrangement very much like the contact 2, and that the cable 5 is similarly connected to it. It will be seen,
30 however, that the movable contact or end piece 41 of the blade 1 does not engage directly with the sides of the U shaped part 40, but is received between contact springs 42 conductively secured to the part 40. The
35 lower ends of these springs 42 fit in slots in ridges on the bottom of the U and are held in place by pins 43, while their free upper ends are curved apart to facilitate entrance of the movable contact 41 between them. At
40 the sides of the U are chambered bosses 44 in which are round ended catches 45 and helical springs 46 that act between the removable covers 47 of the boss chambers and flanges on the catches 45 to force the catches
45 inward. The inner ends of the catches 45 extend through holes in the contact springs 42 and engage in depressions in the sides of the
50 movable contact piece 41 so as to resist accidental opening of the switch without preventing intentional opening,—for which latter purpose the contact piece 41 is provided with an apertured lug 48. A projection 49 on the lower side of the piece 41 prevents the switch from being closed beyond the position for the proper engagement of the
55 spring actuated catches 45. The edges of the part 40 are enlarged and rounded even more than those of the part 2, since the part 40 is intended to serve as a sort of corona
60 shield for the contact springs 42, catches 45 etc.; and the edges of the other switch parts are rounded as far as possible for the same purpose.

It will be understood that the various

parts of the supporting structures 6 and 7 6: all have their edges rounded as much as possible to prevent corona,—especially the screws, nuts, etc., of the clamps 15 and 17 and the caps 13 and 18 and the super-structure platform 12. While this and 7: the overlying of the caps 13 by the platform 12 will generally suffice to prevent corona, it is desirable to employ special measures to prevent it on the caps 18, which are at the same high potential as the switch itself. As 7: shown, therefore, sheet metal corona hoods 50 of rounded Derby hat-like form are interposed between the contacts 2 and 4 and the parts beneath (see Figs. 1, 6 and 7), these hoods extending down around the caps 8: and the upper ends of the insulators 14 and having their lower edge or brim portions turned over and inward and then down, though not necessarily forming a completely closed bead.

For a 300 ampere switch for 140,000 to 150,000 volts, the insulators 11 may be about 20 inches high, the insulators 14 about 24 inches high, and the switch blade 1 about 48 inches long, the dimensions of the other parts being in about the proportions shown to those of the insulators.

What I claim as new and desire to secure by Letters Patent of the United States, is:—

1. An insulating supporting structure for 9: high voltage electrical apparatus comprising a base plate, a plurality of hollow insulator posts mounted thereon in polygonal relation and each secured thereto at its end next the same, a rigid superstructure above 10 the other ends of said insulator posts secured thereto at its side next the base plate, another hollow insulator post above those first mentioned mounted on the other side of 11 said superstructure and secured thereto at its end next the same, and means on the other end of said last-mentioned insulator post for securing the element to be supported thereto.

2. An insulating supporting structure for 11 high voltage electrical apparatus comprising a plate, a plurality of hollow externally ribbed insulator posts mounted thereon and each secured thereto by means externally engaging its end next the plate, a platform 11 superstructure overlying the other ends of said insulator posts and secured thereto at its side next the base, another hollow externally ribbed insulator post mounted on the other side of said superstructure and secured thereto by means externally engaging its end next the same, means for securing the element to be supported to the end of the post externally engaging the same, and a rounded, smooth-surfaced metal corona 12 hood surrounding said last-mentioned securing means and the end of the insulator post.

3. The combination of an insulator, means

on its end for securing the element to be supported, means externally engaging the insulator for securing said means thereto, and a metal corona hood having a rounded, hat-like form and having its edge or brim portion turned over and inward interposed between the supporting means and the securing means aforesaid and extending down

over said securing means and the end of the insulator.

In witness whereof, I have hereunto set my hand this eighth day of May, 1914.

EDWARD M. HEWLETT.
